NICHOLAS S. CLARKE AND AARON L. BOWEN, OF SEATTLE, WASHINGTON, ASSIGNORS, BY MESNE ASSIGNMENTS, TO COMPRESSED FUEL COMPANY, OF SEATTLE, WASHINGTON, A CORPORATION OF WASHINGTON.

FUEL-PRESSING MACHINE.

1,129,455.

Specification of Letters Patent. Patented Feb. 23, 1915.

Application filed December 17, 1912. Serial No. 737,339.

To all whom it may concern:

Be it known that we, NICHOLAS S. CLARKE, a subject of the King of England, and AARON L. BOWEN, a citizen of the United States, residing at Seattle, in the county of King and State of Washington, have invented certain new and useful Improvements in Fuel-Pressing Machines, of which the following is a specification.

10 This invention relates to that class of machines which are employed in the manufacture of artificial fuel and particularly to improvements in the machine shown and described in U. S. Patent No. 949,176, issued 15 Feb. 15, 1910.

The objects of the invention are simplicity and economy in construction, facility in adjustment and repair, steadiness and smoothness in operation, economy in power, and a 20 high degree of efficiency.

The invention consists in improvements to the entire machine and to its various parts and includes principally the construction of the mechanism for operating the plungers, 25 the dies and means for adjusting them, the devices for cutting the sticks of compressed material into predetermined lengths and means for controlling and operating the same, and other details, all of which will be 30 hereinafter described.

The invention is illustrated in the accompanying drawings, in which—

Figure 1 is a side elevation of a machine embodying the present invention shown partly in section to disclose interior portions thereof. Fig. 2 is an end elevation of the same. Fig. 3 is a longitudinal sectional view of the die and associated parts. Fig. 4 is a detail transverse sectional view showing the 40 construction of the tension and guide pulleys for the flexible core. Fig. 5 is a plan view of the mechanism for regulating the devices for cutting the material into desired lengths. Fig. 6 is a front elevational view of certain 45 parts shown in Fig. 5. Fig. 7 is a plan view of the cutter-head shown detached from the machine. Fig. 8 is a detail plan view of the preferred form of reversing driving mechanism for the die adjusting devices.

The reference numeral 10 designates the 50 side members of the machine frame which, as shown, are supported upon a foundation consisting of horizontally disposed girder members 11. Each of said side members is constituted of two inclined legs 12 which are 55 joined from their upper ends by a tie piece 13. Journaled in bearings provided in said tie pieces is a transversely arranged rocker-shaft 14 having keyed or otherwise secured to its protruding ends downwardly extending 60 rocker arms 15. Pitmen 16 connect a pin 15¹ extending through the free ends of said arms with crank pins, such as 17, provided upon toothed gear wheels 18 mounted upon a shaft 19 and rotated by pinions, as 20, provided upon a power driven shaft 21. Said 65 rocker arms are of substantially triangular shapes, as shown in Fig. 1, and are coupled at opposite sides of the rocker shaft by pins 22. The pins 22 are connected by connecting rods 23 with cross heads 24 operating between guides 25 which are secured to the legs 12 of the frame. A plunger 26 is secured to each of the cross heads. The plungers reciprocate through feed hoppers 27 to 70 carry the material into the respective dies therebelow and in which the material is compressed by the plunger. Provided in each hopper is a conveyer screw 27¹ for pushing the material into the path of the 75 plunger. Said conveyer screws are mounted on shafts 27² which are provided with sprocket wheels for a power transmission chain, indicated by 27³.

A die consists of a chambered body 28 85 (Fig. 3) having inserted therein a tube 29 to afford an annular space 30 about the latter for the circulation of cooling water for the maintenance of the die at a suitable temperature. Interiorly of the tube 29 is a 90 bushing 31 and fitted within the latter is a removable liner 32 which serves as the die proper. This liner extends a distance below the bushing and in such protruding portion the liner is formed relatively thin and provided with longitudinal slots 32¹.

As shown in Fig. 3, there is rigidly secured below the body 28 a collar 33 which

supports a discharge pipe 34 which is disposed in axial alignment with the die and plunger therefor. Interposed between the bushing 31 and collar 33 is a rotatable annulus 35 provided upon its inner peripheral surface with screw threads which engage in external threads provided upon a sleeve 36. The sleeve at its upper end is fitted within the tube 29 and interiorly is formed with a 10 tapered bore 36¹ which embraces the opposing tapering surfaces of jaw members 37. The jaw members are desirably hung from the bushing 31 as by the interfitting of a marginal tongue 37¹ provided upon the 15 former within a circumferential groove 31¹ of the bushing. By rotating the annulus 35 in one direction, the sleeve 36 is thrust axially over the jaw members which are thereby pressed concentrically inward to reduce the 20 size of the opening at the lower end of the liner so as to afford requisite resistance upon the material passing through the die and also cause the material to bond itself with the core. When the annulus is turned in a 25 contrary direction, it is withdrawn with respect to the jaw members, whereupon the resiliency of the liner structure will assert itself to restore it to its normal cylindrical condition. For controlling an annulus, we 30 provide thereon peripheral gear teeth, as 35¹, which are engaged by a worm 38 mounted upon a stub shaft 39 rotatable in boxes secured to the machine frame. Shaft 39 is driven from another shaft 40 by means of a 35 chain 41 passing about sprocket wheels 39¹ and 40¹ provided on the respective shafts. Splined to shaft 40 (Fig. 8) is a pair of oppositely disposed bevel friction-wheels 42 and 42¹ integrally connected so as to be moved in unison axially of the shaft, as by a shifter lever 43, to engage one or the other of said friction wheels with a bevel friction pinion 44 which is rotated upon a power driven shaft 45. By means of said friction gear it 45 is evident that the worm shaft 39 may be rotated in either rotary direction to control the opening or closing of the discharge end of the liner, as above explained. To enable the operator to regulate the effective 50 size of the liner, we provide screw threads, indicated by 39² on the worm shaft which engage with gear teeth provided in the periphery of a rotary disk or dial plate 46, Fig. 2, having graduated marks thereon 55 which are employed in conjunction with a pointer 46¹ secured to the frame.

In the manufacture of the fuel, the sawdust, shavings or other material, is pressed about a core of rope or cord 47 which is supplied from reels 48 and through axial bores provided in crossheads 24 and plungers 26. The cord 47 for each plunger is led from a reel to and about pulleys 49 and 50 and from the latter is conducted over a guide wheel 51 into the bores of a crosshead and a

plunger. The pulley 49 is provided with a plurality of grooves, as 49¹, Fig. 4, and is likewise formed with a face 49² to receive a brake-block 52 which is secured to an arm 52¹, said arm being pivotally connected to the frame at 52² and at its free end is hung a weight 53 for applying appropriate tension to the rope. The other pulleys 50 comprise a number of sheaves having a single groove each and are mounted upon a shaft to 70 enable the same to be independently rotated so as to compensate for any irregularities in the size of the rope and distribute the strains more uniformly between the pulleys 49 and 50. As the material is supplied to a die, it 80 is pressed into a cylindrical shape therein by a succession of strokes of a plunger and is forced out of the delivery end of the discharge pipe 34. When it is protruded sufficiently from the pipe it is automatically cut 85 off into predetermined lengths by means of the mechanism which we will now describe.

Rotatable in a plane rectangular to the axis of the discharge pipe and subjacent thereto is a cutter head consisting of four knife blades 54 which extend radially from a shaft 55 having mounted thereon a toothed bevel gear wheel 56 which is in mesh with a similar gear wheel 57 fixedly mounted upon an intermittently driven shaft 58. 90 Shaft 58 has also secured thereon a ratchet wheel 59 provided with teeth 59¹ which are arranged to be engaged upon occasion by a pawl 60 carried by an arm 61 which is vibrated by a connecting rod 61¹ from an arm 62 provided on a rocker shaft 63. Said rocker-shaft receives its motion from rocker-arms 15 by means of a rod 64 which is rigidly secured to the shaft 63 and slidably connected to a block 65 which is swiveled to the pin 15¹. The arm 61 is loosely mounted upon the shaft 58 as is also a substantially circular guard plate 66. This plate is of greater diameter than the ratchet wheel 59 and is provided in its circumference with a recess 66¹ which terminates at a shoulder 66² and is also provided with spaced teeth 66³ and 66⁴, Fig. 6.

67 is a cylindrical casing secured to a bracket 68 which is secured to one of the frame girder members 11. Within said casing is a piston 69 which is urged outwardly by a helical spring 70. Said piston is connected by a rod 71 with a crank pin 72 provided on the guard plate 66 and whereby the power of the spring is applied to yieldingly hold the plate in the rotary position in which it is represented in Fig. 6 and whereat it is arrested by the tooth 66⁴ encountering a fixed stop 68¹.

74 represents a bar carrying an adjustable pedal 75. Said bar is suspended by links 76 and 77 which are hingedly connected to girder members 11 by rods 76¹ and 77¹ to afford swinging up and down movements to 130

the bar 74. The link 77 has connected thereto an arm 77², Fig. 5, which is pressed upwardly from below by a finger 78 provided on the end of a lever 78¹ through the office 5 of a weight 79 which is carried at the other end of the lever. Intermediate of its length the lever 78¹ is secured to a shaft 80 which serves as a pivotal pin therefor. Shaft 80 is journaled in bearings provided and has 10 an arm 80¹ at its outer end. A dog 81 is pivotally connected by a pin 82 to a stationary part of the frame and is provided at one end with a hook 81¹ which is adapted to engage with the guard tooth 66³ when the 15 latter is presented thereto.

83 is a spring tending to swing the dog 81 into engagement with the referred to tooth.

A dog 84 is carried by the arm 80¹ and is 20 actuated by a spring 85 to cause the hooked end 84¹ of this dog to engage over the extremity 81² of the other dog when the arm 80¹ is swung upwardly.

The operation of the above described cutter regulating devices may be explained as 25 follows: When the compressed fuel, in the shape of a stick, is protruded sufficiently far from the discharge pipe 36, it will engage the pedal 75 and the further movement of 30 the stick will cause the bar 74 to be thrust downwardly and swing the links 76 and 77 therewith together with the arm 77². The latter accordingly influences the lever 78¹, in opposition to the power of weight 79, 35 to cause the shaft 80 to be rocked sufficiently to disengage the dog 81 from the tooth 66³ through the medium of the dog 84. The guard plate 66 being thus released from 40 dog 81 is affected by the spring 70 to rotate the plate into the position in which it is shown in Fig. 6, thereby revolving the recess 66¹ into position to allow the pawl 60 to engage one of the ratchet teeth 59¹ when the arm 61 is swung in the next upward 45 movement of the plunger. The ratchet wheel is thus given a fourth of a rotation to correspondingly actuate the cutter head and cut off by one of the knife blades the fuel stick which protrudes from the discharge pipe 34. During the ultimate movement of the pawl 60 it engages the shoulder 66² and causes the guard plate to be moved in unison with the ratchet wheel and in opposition to the spring 70 until the 50 tooth 66³ is carried beyond the hook of the dog to be engaged by the same. By thus advancing the ratchet wheel one-fourth of a turn, a second tooth thereof is brought into position to be engaged by the pawl, but as 55 the recess of the guard plate has been shifted the pawl is restrained from such engagement until the plate has been disengaged from the dog 81 and restored to the position in which it is illustrated through the instru- 60 mentality of the spring 70. By adjusting 65

the position of the pedal the length of the stick of fuel to be cut off is determined and it is obvious that the pawl will remain in operation until the guard plate is affected by a stick pushing down the pedal to release the plate to enable the spring to move it into position to render the pawl operable.

What we claim, is—

1. In a machine of the class described, the combination of a rocker-shaft, vibratory 75 arms provided on said shaft, a die, a plunger arranged to reciprocate in said die, operative connections between said arms and the plunger for actuating the latter when the arms are vibrated, means to vibrate said 80 arms, devices actuated from said arms to cut the fuel, and means controlled by the fuel whereby said devices are regulated to cause the fuel to be cut into predetermined lengths.

2. In a machine of the class described, the combination with a die, a plunger therefor, a rocker-arm operatively connected with the plunger, means actuated by said arms for cutting off fuel as it is projected 90 from said die, devices for rendering said cutting means inoperative, and adjustable devices which are influenced by the fuel for causing the aforesaid devices to become temporarily inoperative whereby said cutting means become operative to cut the fuel 95 into predetermined lengths.

3. In a machine of the class described, the combination with a die, a plunger therefor, a rocker-arm operatively connected with the 100 plunger, means actuated by said arms for cutting off fuel as it is projected from said die, spring controlled devices for rendering said cutting means inoperative, and adjustable devices which are influenced by the 105 fuel for causing the aforesaid devices to become temporarily inoperative whereby said cutting means become operative to cut the fuel into predetermined lengths.

4. In a machine of the class described, the 110 combination with a reciprocating plunger and a die having a contractible delivery end, of power actuated mechanism for regulating the opening of said die, and indicating means operatively connected with said mechanism for indicating the relative amount of opening of said die.

5. In a machine of the class described, the combination with a reciprocating plunger, of a slotted die, jaw-members surrounding 120 the lower portion of the die, a screw-threaded sleeve provided with a tapering bore into which said jaw-members extend, an annulus provided internally with screw threads to engage the threads of said sleeve, 125 and power driven devices whereby said annulus may be rotated to advance or retract the sleeve with respect to the jaw-members whereby the latter are actuated to regulate the effective opening of the die.

6. In a machine of the class described, the combination with an adjustable die, and a reciprocating plunger therefor, of a rotary cutter, and mechanism controlled by the fuel after the same has been forced by the plunger from said die for rendering the cutter operative to cut off the fuel to pre-determined lengths.

Signed at Seattle, Wash., this 4th day of December, 1912.
